UNITED STATES PATENT OFFICE.

MICHEAL MAC MAHON, OF BROOKLYN, NEW YORK, ASSIGNOR TO JAMES W. CHISHOLM, TRUSTEE, OF SAME PLACE.

COMPOUND STEAM-ENGINE.

SPECIFICATION forming part of Letters Patent No. 247,994, dated October 4, 1881.

Application filed December 3, 1880. (No model.)

To all whom it may concern:

Be it known that I, MICHEAL MAC MAHON, of the city of Brooklyn, county of Kings, State of New York, have invented certain new and 5 useful Improvements in Compound Steam-Engines, of which the following is a specification.

This invention has for its object to increase the efficiency of compound steam-engines by more fully utilizing the steam and obviating loss of temperature from radiation of heat. This desirable result I accomplish by a novel construction and arrangement of three double-acting cylinders, each having independent slide-valves, the steam from the boiler being admitted only to the smallest of the three, which 15 is the high-pressure cylinder, and which is centrally located in the second or intermediate cylinder. This intermediate cylinder is provided with an annular piston having two piston-rods connected to the same cross-head as the high-pressure piston-rod. The steam, after actuating the piston of the high-pressure cylinder, passes through a valve-chest and into the intermediate cylinder, from which, after 20 further expanding and actuating the annular piston, it escapes into a receiving-chamber, and from this chamber, in which the slide-valve of the low-pressure cylinder is placed, the steam passes into the third or low-pressure cylinder, 25 and then through an ordinary exhaust-pipe to a surface-condenser, which may be of any of the ordinary constructions. The crank to which is connected the piston of the low-pressure cylinder and the crank to which is connected the pistons of the high-pressure and of the intermediate cylinders may be set at any desired angle 30 relatively to each other on the main shaft. The second and third cylinders are surrounded by steam-jackets. The second cylinder forms a 35 steam-jacket for the first, and all of the exterior surfaces are covered with any suitable non-conductor of heat. The receiving-chamber between the second and third cylinders is provided with a series of pipes horizontally arranged within it, 40 through which some of the heat from the furnace is allowed to pass, thereby reheating the steam in this chamber and preventing condensation taking place, as well as re-evaporating the water in the steam, should any be formed. 45

The casings of this chamber are provided with 50 suitably-placed doors, to afford opportunity for cleaning the tubes.

The invention also consists in a novel arrangement of the steam-chests and steam-passages, and of the application of puppet-valves 55 to the slide-valves of the high-pressure cylinder, which puppet-valves are operated by a new and simply adjustable cut-off mechanism, all of which will be fully described by reference had to the accompanying drawings, forming 60 part of this specification, in which—

Figure 1, Sheet 1, is a longitudinal sectional elevation of my improvements in compound steam-engines. Fig. 2, Sheet 2, is an end elevation, showing the covers of the steam-chests 65 removed. Fig. 3, Sheet 3, is a plan view of the cylinders, with the high-pressure and intermediate cylinders partly in section, through the line *w w*, Fig. 1. Fig. 4, Sheet 3, is a plan view of the general features of the engine, with the 70 cylinders in section, cut through the line *x x*, Fig. 1. Fig. 5, Sheet 4, is a transverse sectional elevation of the low-pressure steam-chest through the line *y y*, Fig. 1. Fig. 6, Sheet 4, is an enlarged view of one of the high-pressure 75 slide-valves, with its puppet cut-off valve and mechanism for operating the same partly in section. Fig. 7, Sheet 4, is a plan view of the same, also partly in section; and Fig. 8, Sheet 4, is an end view of the cut-off device in section through the line *z z*, Fig. 6.

The form of engine shown in the drawings embodying my improvements is of the vertical inverted-cylinder type. The high-pressure cylinder *a* is centrally located in the intermediate cylinder, *b*, which is in line with and on the same horizontal plane as the low-pressure or condensing-cylinder *c*. The piston *a'* of the central cylinder, *a*, is connected by its rod *a'* with the cross-head *d*, as is also the annular 90 piston *b'* of the cylinder *b* by its two piston-rods *b'* *b''*, and the piston-rod *c'* of the low-pressure piston *c'* connects it to the cross-head *e*. These cross-heads *d* and *e* are fitted to slide in guides, and are connected, respectively by 95 the connecting-rods *d'* and *e'*, to their cranks *d''* and *e''* of the main shaft *d''*, in the ordinary manner. The two cranks are shown in the

drawings as set diametrically opposite each other. They may be set in any angular position without affecting my improvements.

f represents the condenser in communication with the low-pressure cylinder *c* by means of the exhaust-pipe *f'*, and *g* is the air-pump, &c., operated from the cross-head *e* by means of the rods and levers *g'* *g''*; and as there is nothing particularly new in the construction and arrangement of these parts of the engine it is unnecessary to more fully describe them.

The steam-chests of the high-pressure cylinder *a* and intermediate cylinder *b*, are located on the side of the cylinder *b*. The steam-chest *h* of the intermediate cylinder, *b*, is between the two steam-chests *i* and *j* of the high-pressure cylinder *a*. Live steam from the boiler enters only these two steam-chests *i* and *j* through the pipe *k*, Figs. 2, 3, and 4, and passage-ways *k'* *k''*, Figs. 3 and 4, connecting them together, and passes into the cylinder *a* alternately to the upper and lower sides of the piston *a'* through the valves *i'* and *j'*, which are of the ordinary slide-valve pattern, but are each provided with a puppet cut-off valve, to be hereinafter described.

The slide-valves *i'* and *j'* are operated by the rod *k'*, which is connected to them by adjusting-nuts, and it passes loosely through a pipe, *k''*, Fig. 1, which is especially provided for the purpose, being cast into the walls of the ports of the intermediate cylinder, being as a passage-way for the rod and also to brace the walls of the ports and join the two steam-chests *i* and *j*, and the rod passes through a stuffing-box in the lower chest, *j*, to the link *k*. This link *k* also carries the rod *h*, which passes up through a stuffing-box and pipe, *h'*, in the chest *j*, and is connected to the double-ported slide-valve *h'*, and has necessarily the same travel as that of the high-pressure valves *i'* and *j'*.

The link *k* is operated by means of two eccentrics and their rods *k'* *k''*, as generally adopted to constitute the operating part of the reversing-gear; and the link *k* is connected to the reversing-wheel *k'* through the medium of its screw-shaft fitting in a nut pivoted to a lever, *k''*, which lever is secured to a shaft, *k''*, working in bearings on the back of the condenser *f*, and the two rods *k'*, pivoted to a plate at the end of the lever *k''* and to the center of the upper and lower sides of the link *k*, thus applying an even strain on the link when it is moved to allow either of the eccentrics *k'* or *k''* to operate the valves; and this construction also admits of the ends of the rods *k'* *k''* passing between the connection of the two valve-rods *k'* and *h* with the link *k*.

The shaft *k''*, Fig. 4, to which the lever *k''* is secured, extends along the rear of the condenser *f*, and has also secured to it the lever *l*, which is connected by the rod *l'* to the link *l*, Fig. 1, forming the connection between the eccentrics and their rods *k'* and *k''* and the valve-rod *m* of the slide-valve *m'*, which is of the same construction as the slide-valve *h'*, and it is located in the steam chest or receiver *m* of

the low-pressure cylinder *c*. This steam-chest *m* is a large chamber between the cylinders *b* and *c*, and is formed on the exterior of the cylinders by casings or jackets *b'* and *c'*, Fig. 4.

Extending laterally through the chamber *m* is a series of pipes, *m'*, which open into chambers formed at the sides of the chambers *m* by plates *m''* *m'''* and flanges *m'''* *m''''*, Figs. 3, 4, and 5, projecting from the sides of the chamber *m*, and so arranged that the heated gaseous products of combustion from the smoke-stack entering through a connecting-pipe the opening *m''* are caused to traverse the whole lengths of the pipes *m''* *m'''* back and forth before they pass away through the opening *m''''*, as shown at Fig. 5. These plates *m''* *m'''* are provided with doors *m''''*, suitably arranged to afford facilities for cleaning the tubes *m'*, and these plates, as well as the valve-chests and cylinder-heads, are covered with some suitable non-conducting material. The cylinder-heads may also be cast hollow, to further provide against loss of heat.

By the arrangement of the receiver *m* above described some of the waste heat of the furnace is utilized to reheat and prevent the steam in the chamber from condensing, so that it may pass into the low-pressure cylinder *c* in a better condition for use than if allowed to pass therein after actuating the piston of the intermediate cylinder, *b*, without being subjected to such extra heating and the re-evaporation of the water carried by it.

The puppet cut-off valves on the backs of the slide-valves *i'* and *j'* of the high-pressure cylinder *a* and their operating mechanism are alike in every respect as regards construction and operation, but are reversed in position, as shown at Fig. 2, so that the following description of the upper one, as shown in the enlarged views, Figs. 6, 7, and 8, will answer for both of them.

On the back of the slide-valve *i'* is formed the open-end cylindrical chamber *n*, connecting the inlet-port of the valve to the interior of the steam-chest *i'*. The ends of this chamber *n* are closed by the double puppet-valve *n'* *n''*, and the ends of its stem fit between the two arms *n''* *n'''*, secured to the shaft *n*, so that there is no end-play, but with sufficient freedom to slide up and between them, so that the puppet-valve *n'* is not affected by the sliding action of the slide-valve *i'*. The valve *n'* is opened and closed at the desired times, irrespective of the movement of the slide-valve *i'*, by motion being imparted to the shaft *n*, which is done in one direction to close the puppet-valve by the spring *n''*, held in the bracket *n'''*, and surrounding the part of the shaft *n* which projects through a stuffing-box on the side of the steam-chest *i*.

A collar on the shaft *n*, against which the spring *n''* bears, carries a spring latch or tappet, *n'''*, which is constructed so as to be held by its spring at a horizontal position, as shown, and operated as hereinafter described.

The vertical shaft *o* is fitted to slide in the

brackets n^5 n^6 , and is connected to the rod p of the eccentric p' . On it are secured the two adjustable cut-off devices, which consist of a carrier, o' , having an inclined projection, o^2 , occupying a given part of the throw of the eccentric p' , which in the drawings is shown as being one-fourth.

A series of rectangular slides, o^3 , are fitted in a slot in the carrier immediately under the inclined projection o^2 , and adapted to be pushed out in line with it by means of a cam, o^4 , having as many sections as there are slides, the rises of the cam-sections being angularly placed, so that the top one is the first to act and the bottom one the last to act on their respective slides, but they all drop off in one line, so that any number of the slides o^3 may be moved and held out by turning the cam o^4 the required amount; or all of the slides may be moved back flush with the side of the carrier o' , leaving the incline o^2 as the only projection, thus determining the length of time the puppet-valve is to be held open, it being opened by the inclined projection o^2 acting against the tappet n^6 as the shaft o moves in an upward direction, and it is so held open until the top edge of the tappet n^6 passes over the lower edge of the incline o^2 , or the lower edge of the lowest slide o^3 , which has been pushed out by the cam o^4 . In the drawings two slides are shown as pushed out, the cut-off in this case taking place at one-half stroke, as each of the slides represents one-eighth of the stroke and the inclined projection o^2 one-quarter. Of course the number of slides and the proportion each one bears to the stroke may be varied as desired. When the shaft o is moving downward after the slides have passed over the tappet and the shaft n^6 has been thrown back to close the puppet-valve by the spring n^4 , then the bottom of the inclined projection o^2 or of the slide in use comes in contact with the top of the tappet n^6 and moves it down out of the way against the action of its spring, allowing the slides and projection to pass without disturbing the shaft n^6 .

The cam o^4 is designed to be turned around by the milled head on the upper end of its shaft, and to be held in any desired position by the spring-catch o^5 falling into one of the holes in a collar on the cam, and the slides o^3 are securely held in either position by a web on the lever fitting into notches formed in their sides. The lever o^6 is prevented from moving out of the notches in the slides by means of a spring-latch.

The high-pressure and annular pistons a' and b' are represented in the drawings as just about to complete their upward stroke. The projection o^2 is about to act on the tappet n^6 to move the puppet-valve, so that this valve is open when the pistons reach the upper ends of their cylinders and before the slide-valve i' has uncovered the port i^2 to let the steam pass through the passage formed in the cylinder-head into the cylinder a , above its piston a' . The slide-valve j' has opened the exhaust-port j^2 before the pistons reach the end of the stroke,

allowing the steam which had forced the piston a' in an upward direction to pass through the passage j^3 into the steam-chest h , and through its inlet-port h^3 to the top of the piston b' , the under side of the piston b' exhausting through the passage h^4 into the interior of the valve h' , and out through the opening h^5 , around the outside of the cylinder b into the chamber m^2 , from which it passes into the low-pressure cylinder c through the port r , the upper part of the cylinder c being now open to the condenser f through the passage r' and exhaust-pipe f' . Just before the pistons have completed their strokes live steam is let into the cylinder a under the piston a' from the steam-chest j through the passage j^3 , the upper part of the cylinder a then exhausting into the chest h through the passages i^2 and i^3 . Steam from the chest h now passes to the under side of the annular piston b' through the passage h^4 . The upper part of the annular cylinder b at the same time is open to the chamber m^2 through the passages h^3 h^5 . The low-pressure cylinder c is now taking steam from the chamber m^2 at its upper part.

From this construction and arrangement of the various parts it will be seen that the live steam from the boiler in performing its work in the cylinder a is protected from radiation by the steam in the intermediate cylinder, b , which, in its turn, is protected by its own exhaust-steam filling the space between the cylinder b and jacket b^3 and the chamber m^2 , the cylinder c also being protected by this steam, which is further heated by the gases of combustion passing through the pipes m^3 .

It is obvious that some of the improvements before described may be applied to steam-engines separately—as, for instance, the puppet cut-off valve, in combination with the slide-valve, and the reheating-pipes passing through the steam-chest of the low-pressure cylinder, and also the arrangement of the valves and valve appurtenances in the steam-chest h and between the steam-chests i and j .

I do not here claim the improvements shown and described relating to the puppet cut-off valve, as such will form the subject-matter of another application.

Having now described my invention, what I claim, and desire to secure by Letters Patent, is—

1. In combination, the high-pressure cylinder a and its piston a' , the cylinder b and its annular piston b' , the high-pressure steam-chests i and j , slide-valves i' and j' , and the intermediate steam-chest, h , and valve h' , substantially as and for the purpose hereinbefore set forth.

2. In combination, the high-pressure cylinder a and its piston a' , the cylinder b and its annular piston b' , the high-pressure steam-chests i and j , connecting-pipe h^6 , slide-valves i' and j' , and the intermediate steam-chest, h , and valve h' , substantially as and for the purpose hereinbefore set forth.

3. The cylinder b , piston b' , and piston-rods

b^2 b^2 , connected to the cross-head d , in combination with the cylinder a , the piston a' , and its rod a^2 , also connected to the cross-head d , with their respective slide-valves and steam-

5 passages, constructed and arranged substantially as and for the purpose set forth.

4. In a compound steam-engine, in combination, the high-pressure cylinder a , located centrally within the intermediate cylinder, b , 10 the intermediate cylinder, b , the low-pressure cylinder c , and the steam-chamber m^2 , connecting the cylinders b and c and partly or wholly surrounding them, substantially as and for the purpose hereinbefore set forth.

15 5. In a compound steam-engine, in combination, the high-pressure cylinder a , valve-chests i and j and their valves i' and j' , the intermediate cylinder, b , valve chest h , and valve h' , the low-pressure cylinder c , and the steam-chamber m^2 , connecting the cylinders b and c , and partly or wholly surrounding them, substantially as and for the purpose hereinbefore set forth.

6. In combination with the steam-chamber 25 m^2 , located between and connecting the cylinders b and c , the pipes m^3 m^3 , arranged substantially as described and adapted to act as flues, through which heated gases from the smoke-stack or furnace are caused to pass, as

30 and for the purpose hereinbefore set forth.

7. In combination with the links k^2 and eccentrics k^3 k^4 , the valve-rod k' , carrying the

two high-pressure valves i' and j' , and the rod h^2 , carrying the valve h' of the intermediate cylinder, b , substantially as hereinbefore set forth.

8. The cut-off device composed of the vertically-moving shaft o , carrier o' , having inclined projection o^2 , slides o^3 , adjusting-cam o^4 , spring-latch o^5 , and the horizontally-moving 40 shaft n^3 , provided with the spring-tappet n^6 and spring n^4 , all constructed and combined substantially as and for the purpose hereinbefore set forth.

9. As an improvement in compound steam- 45 engines, in combination, the high-pressure cylinder a , intermediate cylinder, b , low-pressure cylinder c , receiving-chamber m^2 , reheating-pipes m^3 m^3 , valve-chests i , j , and h , valves i' and j' , connected to link k^2 by rod k' , valve h' , also connected to link k^2 , rods k^7 , arm k^6 , hand-wheel k^5 , eccentrics and rods k^3 k^4 , shaft k , rods and link l l' l^2 , and valve m' , eccentrics and rods l^3 l^4 , cross-head d , and pistons a' and b' , cross-head e and piston c' , connecting-rods 50 d' and e' , and double-crank shaft d^3 , constructed and operated substantially as and for the purpose set forth.

In testimony whereof I have hereunto set my hand this 2d day of December, A.D. 1880. 60

M. MAC MAHON.
